US00D548350S

(12) **United States Design Patent** (10) **Patent No.:** **US D548,350 S**
Jordan et al. (45) **Date of Patent:** **** Aug. 7, 2007**

(54) **PAD ORNAMENTATION FOR APPENDAGE WRAP**

(75) Inventors: **Robert H. Jordan**, Stillwater, MN (US); **James L. Young**, Richfield, MN (US)

(73) Assignee: **3M Innovative Properties Company**, St. Paul, MN (US)

(**) Term: **14 Years**

(21) Appl. No.: **29/257,469**

(22) Filed: **Apr. 4, 2006**

(51) **LOC (8) Cl.** **24-01**

(52) **U.S. Cl.** **D24/190**

(58) **Field of Classification Search** **D24/190-3; 602/4-6, 20, 27, 61-2, 79; 128/865-6, 878, 128/876; 604/20-21; 24/442; D29/113; 473/62; D6/601**

See application file for complete search history.

(57) **CLAIM**

The ornamental design for a pad ornamentation for appendage wrap, as shown and described.

DESCRIPTION

FIG. 1 is a perspective view thereof;

FIG. 2 is a top view thereof;

FIG. 3 is a side view thereof (the view from the other side is a mirror image);

FIG. 4 is a bottom view thereof;

FIG. 5 is an end view, as taken from the left in FIG. 2; and, FIG. 6 is an end view, as taken from the right in FIG. 2.

The dashed lines in FIGS. 1-6 do not form a part of the claimed design.

The broken line showing of an appendage wrap is included for the purpose of illustrating environmental structure and forms no part of the claimed design.
